US0D1037272S

(12) **United States Design Patent** (10) **Patent No.:** **US D1,037,272 S**
(45) **Date of Patent:** **** Jul. 30, 2024**

(54) **DISPLAY SCREEN OR PORTION THEREOF
WITH A GRAPHICAL USER INTERFACE
FOR A MEDICAL DEVICE**

(71) Applicant: **Neucures Inc.**, Los Angeles, CA (US)

(72) Inventors: **Padmaja Narsipur**, Bangalore (IN);
Koduvayur Ramakrishnan
Subramanyan, Bangalore (IN)

(73) Assignee: **NEUTRACE INC.**, Longwood, FL
(US)

(**) Term: **15 Years**

(21) Appl. No.: **29/791,806**

(22) Filed: **Feb. 9, 2022**

(51) LOC (14) Cl. **14-04**

(52) U.S. Cl.

(57) **CLAIM**

The ornamental design for a display screen or portion thereof with a graphical user interface for a medical device, as shown and described.

DESCRIPTION

The single FIGURE is a front elevation view of a display screen or portion thereof with a graphical user interface for a medical device showing our new design.

The broken lines showing the outer border of the display screen or portion thereof and the interior features of the graphical user interface in the drawings forms no part of the claimed design. The gray broken lines of the graphical user interface forms no part of the claimed design.

1 Claim, 1 Drawing Sheet
